B. B. WICKEY.

APPARATUS FOR RECLAIMING PAPER AND PARAFFIN WAX.

APPLICATION FILED OCT. 20, 1919.

1,431,553.

Patented Oct. 10, 1922.

UNITED STATES PATENT OFFICE.

BERTRAM B. WICKEY, OF EAST CHICAGO, INDIANA.

APPARATUS FOR RECLAMING PAPER AND PARAFFIN WAX.

Application filed October 20, 1919. Serial No. 331,928.

To all whom it may concern:

Be it known that I, BERTRAM B. WICKEY, a citizen of the United States, and a resident of East Chicago, Lake County, and State 5 of Indiana, have invented certain new and useful Improvements in Apparatus for Reclaiming Paper and Paraffin Wax, of which the following is declared to be a full, clear, and exact description.

- 10 This invention relates to apparatus for and method of reclaiming paper and paraffin or wax from paraffin or wax waste material, and its primary object is to provide an improved apparatus and method, whereby a 15 continuous process of reclaiming paper and paraffin or wax may be carried on, that is to say, whereby when the apparatus is set in motion, the reclaiming process may be carried on indefinitely without the necessity of 20 stopping and starting the apparatus each time a fresh batch of material is introduced into the apparatus. Another object is to increase the capacity of apparatus of this character, without necessarily increasing its size. 25 Another object is to separate the paraffin or wax from the material containing it without the necessity of distilling or otherwise separating it from the chemical used in removing it from the material.
- 30 It is well known that much waste paper contains paraffin or wax, and one of the principal objects of this invention is to separate the paraffin or wax from paraffin or wax paper, whereby the freed paper may be 35 put to useful purposes, and the paraffin or wax may be saved.

With these and other objects and advantages in view this invention consists in any apparatus embodying a chemical bath for 40 liberating the paraffin or wax from waste material, and a conveyor for the material, traveling through the bath and moving and agitating the paraffin or wax paper or other material in the bath for a sufficient time to 45 permit the bath to act on it and liberate the paraffin or wax. The invention further consists in the method of liberating or removing paraffin or wax from waste material containing paraffin or wax which consists in 50 conveying the said material through a bath containing a suitable paraffin liberating agent for a sufficient time to remove the paraffin or wax. The invention further consists in the several novel features herein- 55 after fully set forth and claimed.

The invention is clearly illustrated in the accompanying drawing, in which—

Fig. 1 is a plan partly broken away of an apparatus embodying a simple form of the present invention; Fig. 2 is a vertical 60 longitudinal section taken on the broken line 2—2 of Fig. 1; Fig. 3 is a cross section taken on line 3—3 Fig. 2; and Fig. 4 is a vertical cross section taken on line 4—4 of Fig. 2.

Referring to said drawing, the reference 65 character 5 designates a tank or vat, which may be of elongated rectangular form having sides 6, ends 7, and bottom 8; if desired a top 9 may be used as a cover for the tank. In the vat is a steam coil 10 for heating the 70 chemical or solution contained in the tank. A suitable compound, mixture or solution 13 is contained in the tank, and is preferably maintained at a high temperature by the hot steam coil. Said compound, mixture 75 or solution may comprise benzine, benzol, gasoline or other suitable volatile fluids, but I prefer to employ a chemical comprising hydrated sodium carbonate, in the proportions of one pound of sodium carbonate to 80 one gallon of water. A paraffin or wax removing agent of this type has the effect of softening and removing the paraffin or wax from the waste paper and floating it to the top of the bath in a comparatively free state, 85 as shown at 14, whereby the paraffin or wax, as it accumulates, may be drawn off through a normally closed hole or other outlet 15.

In the embodiment of the invention illustrated, the tank is divided into a plurality of 90 connected passage ways, which form one long continuous passage way, the object being to provide means whereby the waste paper may be kept submerged for a comparatively long period of time, and yet permit the operation to be continuous. Conveniently, the long passage is provided by placing in the tank a plurality of lengthwise extending partitions 16 that extend part way up from the bottom 8. The partitions 95 stop short of the ends of the tank to afford communication between the adjacent ones as shown. At one end of the tank is an intake 21 through which the waste paper is fed to the apparatus, and at the other end of the 100 continuous passage way is a discharge opening 22, through which the reclaimed waste paper is discharged into a washing tank or other receptacle. The intake end 21 and discharge end 22 are in communication only 105 110

with the intake and discharge ends respectively, of the passageway. Crosswise extending baffle plates 26, 26^a, project down from the top of the tank at the intake and 5 discharge ends of the passageway and extend into the paraffin softening and removing agent and provide inverted dam like means between the intake opening and passageway and between the passageway and 10 discharge opening, thereby operating to confine the removed paraffin or wax to the passage way between its intake and discharge ends as shown at 14 in Fig. 2.

Horizontally extending screens or other 15 reticulated fabric 20 are placed in the tank between the lower edges of the baffle plates, said screens extending across the tank from one end to the other except at the inlet and discharge openings, acting as a horizontal 20 open work wall or partition, spaced intermediate the top and bottom of the tank and forming with the sides and ends of the tank and with the partition 16 a continuous passage way or channel opening upward 25 through the screen, whereby the paraffin or wax which is liberated from the paper, may rise, pass through the screen and float on top of the chemical in the upper space between the baffle plates 26, 26^a.

30 Any suitable means may be employed for conveying the waste paper material through the passage way below the screen, from the intake to the discharge opening, and for agitating it during its travel through 35 said passage way, and for convenience I have illustrated conveyors in the form of propeller blades 17 fast on shafts 18, extending lengthwise in the passage ways below the screen, from end to end of the tank and journaled in bearing boxes secured to the ends of the tank. Intermeshing gear wheels 19 are shown as fast on said shafts outside of one end of the tank for gearing the shafts 40 together and one of said shafts may be slowly rotated by any suitable source of power in the proper direction to cause the propellers to move the chemical or other paraffin or wax removing agent, and there- 45 with the waste paper through the screened passage way from the intake end to the discharge end thereof. The speed of travel of the propellers should be sufficient to agitate and tumble the waste paper around in the bath, whereby the paraffin or wax may 50 rise from any pockets in the crushed paper. It is understood that waste paper is usually compressed into bales for shipment, and by agitating the crumpled paper in the bath any pockets that are formed therein, which 55 contain the liberated paraffin or wax are shifted around frequently when traveling through the long passage way, permitting the liberated paraffin or wax to escape and float to the top of the solution or chemical agent. The waste paper may be de-

livered and fed to the intake opening in any suitable manner and means are provided for discharging it from the discharge opening. As shown, an elevator is employed for this purpose, which comprises an endless 70 belt conveyor 23 having flights 24 connecting two endless chain belts 25 that are trained around sprocket wheels 27, fast on the shaft 18 at the discharge end and sprocket wheels 28, carried by a shaft 29 75 journaled in brackets 30 supported by the tank. The belts 25 pass around idlers 31 journaled in the brackets 30 below the sprocket wheels 28, thus providing a simple expedient for making a bend in the conveyor as it passes the idlers 31, to thereby dump the freed waste paper into a washing tank or other receptacle.

In the operation of the apparatus the waste paraffin or wax paper is fed into the 85 intake opening and slowly conveyed through the heated chemical in the screened passage way to the discharge end, by the conveyor which also agitates the crumpled paper as above set forth. The agent acts on 90 the paper in the bath and liberates the paraffin or wax which floats to the top and is drawn off when desired. The elevator lifts the freed paper through the discharge opening, and discharges it from the tank. 95

From the above it is apparent that waste paraffin or wax paper may be converted into stock for the manufacture of paper and the paraffin or wax may be cleansed and used for various commercial purposes. 100

More or less variation of the exact details of construction is possible without departing from the spirit of this invention; I desire, therefore, not to limit myself to the exact form of the construction shown and 105 described, but intend, in the following claims, to point out all of the invention disclosed herein.

I claim as new, and desire to secure by Letters Patent:

1. An apparatus of the character described, comprising a tank for containing a paraffin or wax removing fluid, a conveyor for the material from which the paraffin or wax is to be removed, traveling under the surface of the fluid, and means under the surface of the fluid for holding the material under the surface thereof. 110

2. An apparatus of the character described, comprising a tank for containing a paraffin or wax removing fluid, a combined agitator and conveyor for the material, from which the paraffin or wax is to be removed, traveling under the surface of the fluid, and means under the surface of the fluid for holding the material under the surface thereof. 120

3. An apparatus of the character described, comprising a tank for containing a paraffin or wax removing fluid, a conveyor 125

for the material from which the paraffin or wax is to be removed, traveling under the surface of the fluid, and a screen in the fluid above the conveyor for holding the material 5 below the surface of the fluid.

4. An apparatus of the character described, comprising a tank for containing a paraffin or wax removing fluid, a combined agitator and conveyor for the material, 10 from which the paraffin is to be removed, traveling under the surface of the fluid, and a screen in the fluid above the conveyor for holding the material below the surface of the fluid.
- 15 5. An apparatus of the character described, comprising a tank for containing a paraffin or wax removing fluid, and having a baffle plate at each end projecting below the surface of the fluid, a screen connecting 20 the bottoms of said baffle plates and a conveyor traveling under said baffle plates and screen.
6. An apparatus of the character described, comprising a tank for containing a 25 paraffin or wax removing fluid, and having a baffle plate at each end projecting below the surface of the fluid, a screen connecting the bottoms of said baffle plates, a shaft and propellers on said shaft under said screen.
- 30 7. An apparatus of the character described, comprising a tank for containing a paraffin or wax liberating agent, said tank having an intake end and a discharge end, and a passage way therebetween, baffle 35 plates extending down into said agent at the ends of said passage way, and a means for conveying material in said passage way under the surface of said agent from the intake to the discharged end.
- 40 8. An apparatus of the character described, comprising a tank for containing an

agent for liberating paraffin or wax from paraffin or wax waste material, partitions in said tank dividing it into a long continuous passage way having an intake and a discharge end, a horizontal screen submerged in said agent and forming the top of said passage way, baffle plates at the ends of said passage way projecting down into said agent, and a conveyor in said passage way 50 below the screen.

9. An apparatus of the character described, comprising a tank for containing an agent for liberating paraffin or wax from paraffin or wax waste material, partitions in 55 said tank dividing it into a long continuous passage way having an intake and a discharge end, a horizontal screen submerged in said agent and forming the top of said passage way, baffle plates at the ends of said 60 passage way projecting down into said agent, and a conveyor in said passage way below the screen, having a plurality of propeller blades for agitating and propelling material through said passage way.

65 10. An apparatus of the character described, comprising a tank for containing a paraffin or wax remover, baffle plates extending down into said agent and defining the ends of a passage way, and means for agitating and conveying material through said 70 passage way below the surface of said agent.

11. An apparatus of the character described, comprising a tank for containing a paraffin or wax remover, baffle plates extending down into said agent and defining the 75 ends of a passage way, means for agitating and conveying material through said passage way below the surface of said agent, and an elevator at the discharge end of said 80 passage way.
